 P. R. Mallory & Co., Inc., Indianapolis, Ind., a
 corporation of Delaware

Application September 1, 1937, Serial No. 161,941

13 Claims. (Cl. 200—166)

This invention relates to electric switch terminals.

An object of the invention is to provide an improved contact terminal for electric switches.

5 Other objects of the invention will be apparent from the following description and accompanying drawings taken in connection with the appended claims.

The invention comprises the features of construction, combination of elements, arrangement of parts, and methods of manufacture and operation referred to above or which will be brought out and exemplified in the disclosure hereinafter set forth, including the illustrations in the drawings.

15 In the drawings:

Figure 1 is a perspective view of a switch terminal embodying features of the present invention;

Figure 2 is a perspective view of a modified terminal member;

Figure 3 is the face view of an electric switch;

Figure 4 is a section on the line 4—4 of Figure 3;

Figure 5 is a face view of another form of electric switch;

Figure 6 is a section on the line 6—6 of Figure 5.

Figure 7 shows a further modified form of switch terminal;

Figure 8 is a face view thereof;

Figure 9 shows an electric switch embodying said contacts; and

Figure 10 is a section on the line 10—10 of Figure 9.

A feature of the present invention resides in a novel contact terminal design embodying cooperating terminal fingers integrally formed from a single piece of sheet metal.

While a preferred embodiment of the invention is described herein, it is contemplated that considerable variation may be made in the method of procedure and the construction of parts without departing from the spirit of the invention. In the following description and in the claims, parts will be identified by specific names for convenience but they are intended to be as generic in their application to similar parts as the art will permit.

In electric switches of the type used in radio sets and similar equipment, such as for changing the connection of inductance coils and condensers it is of paramount importance that the switches operate with ease and still provide positive action and provide perfect low resistance contact at all times. It is also a requisite that the terminals have the necessary electrical char-

acteristics for use with high frequency and ultra high frequency radio currents.

Contact terminals have been made in the past in which a single contact surface was provided to cooperate with a moveable contact member and contacts have also been provided having a pair of cooperating fingers adapted to receive the moving contact member between them. The latter type of contact is sometimes of advantage since the two cooperating contact areas insure that perfect electrical connection will be made under all circumstances. However, in the past difficulty has frequently been experienced in providing a contact terminal wherein the two cooperating surfaces were accurately spaced and remained in perfect adjustment with subsequent use and abuse. It has been a frequent experience to find one of the contacting portions bent out of alignment with the other. This frequently occurs during the operation of securing and soldering wires to the soldering terminals of the contact.

The contact of the present invention overcomes these difficulties and others and is more economical to manufacture than most similar contacts of the prior art.

Referring to the drawings Figure 1 shows a preferred form of my contact terminal 10 formed of a strip of sheet metal such as phosphor bronze or other conductive spring metals. The contact is shaped by one or more stamping and punching operations.

In these operations the elongate thin, flat strip of metal 10 is given the form shown in Figure 1 comprising a central body portion 11 having a punched hole 12 for securing the contact terminal to the switch base. At one end of portion 12 the strip 10 is bent to provide a shallow U-shaped portion 13 which aids in positioning the terminal on the switch base as will be further described. A soldering lug 14 extends from the outer edge of the U-shaped portion 13 and is provided with an elongate opening 15 which aids in securing and soldering a wire thereto. Soldering lug 14 provides a convenient means for securing the circuit wires to the switch terminal.

The opposite end of strip 10 adjacent to central table portion 11 is punched to provide a tongue 16 framed by a closed loop formed of the bordering material. The contact tongue 16 is disposed between the two arms 17 and 18 of the loop shaped frame or tongue, the ends of arms 17 and 18 being joined by a cross portion 19 at their outer ends. The tongue 16 is bent down at a slight angle with the plane of table 55

portion 11 and is formed at its end into a convex rounded contact surface 20. Arms 17 and 18 are bent into upwardly rounded arches whereby cross portion 19 is retracted to a position immediately 5 facing the convex contact surface 20 of tongue 16. Cross portions 19 is formed into a convex rounded face opposing contact face 20.

The terminals 10 may be secured to a switch base 21 of sheet insulation, such as sheet Bakelite, by means of rivets 22 passing through holes 12 in the terminals. The base 21 may be provided with edge notches 23 into which the U-shaped portions 13 of the terminals fit to secure the terminals against turning. Terminal lugs 15 14 extend beyond the edge of the base to provide circuit connections. Rectangular apertures 24 are provided in the switch base, directly behind the contact tongues 16 to allow them to spring back when the rotor contact engages them. 20 However, the switch base engages each tongue 16 near its base and thereby straightens it into a plane flush with the face of the switch base. This also operates to bring contact face 20 into contact with face 19 subject to being temporarily 25 spread apart by the rotor contact when it engages a particular contact 10 in the operation of the switch.

The switch rotor may be mounted to turn in a bushing 25 secured in an aperture in the switch 30 base and may comprise a rotor shaft 26 passing through bushing 25, to the end of which the rotor contact arm 27 is secured by upsetting the end of the shaft.

Rotor contact arm 27 extends in a direction 35 transverse of the shaft axis and terminates at one end in a flat contact portion 28 adapted to travel in a path between contact faces 19 and 29 of the stator contacts upon rotation of shaft 26. The contact portion 28, upon engaging any stator 40 contact 10, separates contact faces 19 and 29 sufficient for the rotor contact portion 28 to enter between them and make electrical contact with both.

The opposite end of rotor contact arm 27 has 45 material removed from the body thereof to provide a central slot between two side arms and is bent to provide a U-shaped portion 29. The free end of the contact arm, beyond the U-shaped portion, extends down along the side of bushing 50 25. Bushing 25 is at this place, provided with an integral rim 30 in which a series of teeth 31 are cut. The end of contact arm 27 rests against the toothed portion of rim 30 and is provided with an indexing projection 32 which, in 55 co-operation with the teeth, provides an index means for the rotor contact so that it may be set on any stator contact desired.

Figure 2 shows a modified switch contact terminal 40 having another means for mounting on a switch base. The portions 44, 45, 46, 47, 48, 49 and 50 are similar to the portions 14, 15, 16, 17, 18, 19 and 20 respectively of contact terminal 10. The difference resides in the mounting means which here comprises a U-shaped loop 43 formed 65 in the mid-portion of the contact terminal. The middle of the loop is cut to provide a narrowed portion 41 adapted to be crimped to secure the contact terminal to the switch base.

The mounting of terminals 40 in a switch is 70 shown in Figures 5 and 6. The switch base 51 of sheet insulation is provided with a number of H-shaped apertures 53 into each of which the U-shaped portion 43 fits. The shoulders 42 will then be substantially flush with the back surface 75 of switch base 51. Narowed portion 41 may be

crimped as shown to secure the terminal to the base.

The remainder of the switch is generally similar to the one previously described but in this switch the rotor contact arm 57 is provided with two contact shoe portions 58 which make contact with two stator contacts simultaneously or in any sequence desired.

The modified switch terminal shown in Figures 7, 8, 9 and 10 embodies similar ideas of construction to the terminals already described and in addition is so formed as to enable two such switch terminals to be mounted on opposite faces of a switch base and still occupy the same switch position.

Terminal 70 comprises a central body portion formed into a loop 71 for mounting the terminal in substantially the same manner as terminal 40 is mounted. A soldering lug 72 extends outwardly in one direction from loop portion 71 and the contacting portions 73 and 74 extend in the other direction from the loop 71. Contacting portions 73 and 74 are generally similar to the contact tongue previously described. Portion 73 differs, however, in that its free end is bent in 25 the manner shown to provide a cutting edge contact. This contact portion is thus adapted to make a very positive contact with the cooperating contact shoe which slides between the two contacting portions in operation of the switch, contact portion 73 being adapted to cut through any dirt or tarnish on the contacting surfaces and make positive metal-to-metal contact. Contacting portion 74, on the other hand, is of the same form as previously described and not only serves as an 35 additional contact but also helps in keeping the contacting shoe in engagement with contact portion 73.

An important feature of this modification is best illustrated in Figure 9. It will be noted that the central portion 71 of terminal 70 is not disposed on a straight line drawn through the two ends of the terminal but is laterally offset therefrom. It is therefore possible, as shown in Figure 9 to mount one terminal 70a in one mounting 40 hole in stator 75 and to mount another similar terminal 70b on the opposite face of stator disc 75 in another mounting hole so that the two terminals are effectively isolated from each other. Because of the offset relation, however, the soldering lugs 72a and 72b are situated in the same 45 terminal position. The active contact terminals 72a, 74a and 73b, 74b are also positioned in the same contact position on the two opposite sides of the stator. It will be evident that contact 50 terminal 72a may be arranged to make contact with one rotor contact shoe 77 mounted on one face of rotor 76 and that contact 70b will operate with rotor shoe 78 mounted on the other face of the rotor substantially as shown in Figures 9 and 10. Heretofore, when it was desired to mount two terminals in the same switch position on opposite sides of the stator disc additional insulating means have been necessary to keep the two terminals insulated from each other. 55

It will be noted that the terminal as formed allows ample space between the contact faces for silver plating to be deposited on the contacting surfaces.

Another advantage of this type of switch resides in the fact that the wire-securing lug may be bent at any angle without disturbing the alignment, positioning or spring tension on the contact fingers.

There is also obtained an increased length of 76

spring arm due to the shape of the spring arms and the spring action is also improved by the bifurcated nature of the spring arm.

While the present invention, as to its objects and advantages, has been described herein as carried out in specific embodiments thereof, it is not desired to be limited thereby but it is intended to cover the invention broadly within the spirit and scope of the appended claims.

10. What is claimed is:

1. A contact terminal for electric switches comprising a single strip of sheet metal having one end punched to form a tongue and a continuous metal border surrounding said tongue, the parts being bent in relation to each other to provide opposed contact surfaces adapted to engage directly opposed portions on opposite faces of a contact inserted between said surfaces, one of said surfaces being the end of said tongue and the other of said surfaces being the cross-portion of said border formed of material originally beyond the end of said tongue.

2. A contact terminal comprising a piece of sheet metal formed into a securing portion, a tongue extending therefrom, a pair of arms secured thereto at the two sides of the base of said tongue and formed into corresponding arches at the two sides of said tongue, said arms being joined at their ends by a bridging portion disposed in opposed relation to the end of said tongue, whereby said tongue end and said bridging portion form opposed contact surfaces adapted to engage directly opposed portions on opposite faces of a contact inserted between said surfaces.

3. A contact terminal formed of a strip of sheet metal and comprising a central mounting portion of a single thickness of said sheet metal having means for securing said contact terminal to a switch base, a wire-securing terminal at one side of said mounting portion and a pair of contact fingers at the opposite side of said mounting portion, both of said fingers being integrally attached to said single thickness mounting portion and having contact faces at their ends disposed in opposed face-to-face relation to each other, whereby said contact faces are adapted to engage directly opposed portions on opposite faces of a contact shoe inserted between said faces.

4. A contact terminal formed of a strip of sheet metal and comprising a central mounting portion having means for securing said contact terminal to a switch base, a wire-securing terminal at one side of said mounting portion and a pair of contact fingers at the opposite side of said mounting portion, both of said fingers being integrally attached to said mounting portion and having contact faces at their ends disposed in directly opposed face-to-face relation to each other whereby said contact faces are adapted to engage directly opposed portions on opposite faces of a contact shoe inserted between said faces, one of said fingers comprising a frame of metal derived from the region bordering said other finger.

5. A contact terminal formed of a strip of sheet metal and comprising a central mounting portion having means for securing said contact terminal to a switch base, a wire-securing terminal at one side of said mounting portion and a projecting area on the opposite side of said mounting portion, said projecting area being punched to form a tongue and a continuous metal border surrounding said tongue, the parts

being bent in relation to each other to provide directly opposed contact surfaces adapted to engage directly opposed portions on opposite faces of a contact inserted between said surfaces, one of said surfaces being the end of said tongue and the other of said surfaces being the cross-portion of said border formed of material originally beyond the end of said tongue.

6. A contact for electric switches comprising a pair of contact tongues of sheet metal arranged so as to engage opposite faces of a contact shoe in operation of a switch, one of said tongues having a contacting surface comprising a portion of the face of said tongue, the other of said tongues having a contacting surface comprising an edge of said tongue.

7. A contact terminal for electric switches comprising a single strip of sheet metal having at one end thereof a pair of contact tongues, one of said tongues comprising a frame formed of the metal surrounding the other of said tongues, the edge of said frame-shaped tongue comprising its contacting surface.

8. A contact terminal for electric switches comprising a single strip of sheet metal having at one end thereof a pair of contact tongues, one of said tongues comprising a frame formed of the metal surrounding the other of said tongues, the edge of said frame-shaped tongue comprising its contacting surface and the face of said other tongue comprising its contacting surface, the edge contacting surface of said frame shaped tongue being opposite to the contact face of said other tongue.

9. An electric switch comprising a stator of sheet insulating material, an aperture therein, a bushing secured in said aperture, said bushing having an integral flange thereon, stator contacts mounted on said stator, and a rotor comprising a shaft pivoted in said bushing and a rotor arm secured to the end thereof, said rotor arm having at least one contacting portion engaging said stator contacts and an indexing arm, said flange on said bushing having indexing inundations around at least a portion of its periphery and said indexing arm having a projection engaging said inundations.

10. A contact terminal for electric switches comprising a strip of sheet metal having a central mounting portion, a wire securing tongue at one end and a contacting portion at the other end thereof, said central mounting portion being laterally offset to one side of a line through the two ends of said strip whereby said central mounting portion may be secured to a stator plate in a position different from the position occupied by the wire securing tongue and the contacting portion.

11. A switch stator assembly comprising a stator of sheet insulating material and a pair of stator contacts secured on opposite faces thereof, said contacts comprising elongated sheet metal members each having a wire securing portion at one end thereof, a contacting portion at the other end thereof and an attaching portion at an intermediate point thereof, said intermediate point being laterally offset to one side of a line through the two ends of said member, the wire securing portions and contacting portions of both of said members occupying a single stator position, the attaching portions occupying positions offset respectively to the right and to left of said position.

12. A contact terminal for electric switches comprising a strip of sheet metal having a cen-

- 5 tral mounting portion, a wire securing tongue at one end and a contacting portion at the other end thereof, said central mounting portion and said contacting portion being angularly disposed 5 in relation to each other, whereby said central mounting portion may be secured in a radial position to a stator plate in an angular position different from the position occupied by the contacting portion.
- 10 13. A switch stator assembly comprising a stator of sheet insulating material and a pair of stator contacts secured on opposite sides thereof,

5 said contacts comprising elongated sheet metal members each having a wire securing portion at one end thereof, a contacting portion at the other end thereof and an attaching portion at an intermediate point thereof, said attaching portion and said contacting portion being angularly disposed in relation to each other, the contacting portions of both of said members occupying a single stator position, and the attaching portions occupying positions offset respectively to the right and to 10 the left of said position.

GEORGE O. PUERNER.
